UNITED STATES PATENT OFFICE.

GEORGE KAMMERER, OF WHITTIER, AND FRANK HILL, OF LOS ANGELES, CALIFORNIA, ASSIGNEES TO SPENGLER CORE DRILLING COMPANY, OF LOS ANGELES, CALIFORNIA, A CORPORATION OF CALIFORNIA.

ROTARY CORE DRILL.

Application filed September 15, 1924. Serial No. 737,733.

This invention relates to a rotary core drill of the type employed for drilling and testing formations and deep oil wells by the rotary method.

5 The rotary core drills now employed for drilling and testing formations in deep oil wells are generally of the so-called double barrel type, i. e., the core drills comprise a barrel to receive the core formed by the drill 10 and an outer barrel which is employed for the two-fold purpose of passing flushing fluid to the cutters of the drill, the flushing fluid passing outside of the core receiving barrel, and to provide a support for certain 15 outer cutters of the drill which outer cutters are employed to drill the hole to a larger diameter than that of the core extracted.

An object of the present invention is to 20 provide a simplified and improved rotary core drill which employs but a single barrel, the core drill having the single barrel forming a core receiving chamber and including separate passages for the flushing fluid to be supplied to the drill, the single barrel also supporting both the core forming cutters of the drill and the bore enlarging cutters. The single barrel forming both the 25 flushing passages and the core receiving chamber, while the core forming cutters are secured to the single barrel, permits the customary outer barrel to be eliminated and results in a more rigid and sturdy drill.

Another object of the present invention is 30 to provide a rotary core drill so constructed that the flushing fluid passed to the cutters is prevented from destroying the core as formed and thereby provide a rotary core drill which will positively take a true core 35 of the formation in the well.

Various other objects and advantages of this invention will be apparent from a description of the preferred form of rotary core drill embodying the invention. For 40 this purpose, reference is made to the accompanying drawings illustrating a preferred example of the invention.

In the drawings:

Figure 1 is an elevation of the rotary core 45 drill.

Fig. 2 is an elevation in vertical section of the drill shown in Fig. 1.

Fig. 3 is a section on the line 3—3 of Fig. 1.

Fig. 4 is a section on the line 4—4 of 55 Fig. 1; and

Fig. 5 is a section on the line 5—5 of Fig. 1.

Referring to the drawings, 1 indicates a tube forming part of the single barrel of 60 the drill such tube 1 being threaded at its lower end into a joint 2 forming a continuation of the single barrel of the drill, such joint 2 being in turn threaded at its lower end to a tubular cutter 3 forming a 65 further continuation of the single barrel. The tube 1, joint 2 and hollow cutter 3 have vertical core receiving passages 4, 5 and 6, respectively, registering to form a straight vertical core receiving chamber for the drill. 70 The upper end of the tube 1 is threaded into a joint 7 in turn threaded at its upper end to a drill pipe 8 by which the rotary core drill may be operated from the top of the well. The joint 7 is also provided with 75 threaded bore 9 aligned with the bore 4 of the tube 1, into which is threaded a valve cage 10 carrying a valve seat 11 upon which a ball valve 12 normally rests, the ball valve 12 preferably being normally urged against 80 the said seat by a compression spring 13 disposed between the upper side of the ball and top of the valve cage 10. The drill is thus provided with a self-closing or check valve operative to prevent flushing fluid from 85 the drill pipe 8 passing into the core receiving chamber, the valve being, however, operative to permit discharge of flushing fluid out of the core receiving chamber when the core is being admitted thereto. 90

The joint 7 is also provided with a plurality of vertically extending and circumferentially spaced apart flushing ducts 14 communicating with the interior of drill pipe 8 such flushing ducts 14 at their lower end 95 registering with the bores of pipes 15 extending between the joint 7 and joint 2, which pipes are preferably rigidly secured to the tube 1 by a welding process so that the pipes 15 and the tube 1 are in fact integral. The joint 2 is also provided with flushing ducts 16 registering with the bore of pipes 15 which discharge from the lower end of the joint 7.

The hollow cutter 3 of the drill is provided 105 at its lower end with suitable core forming cutter such as mill teeth 17 which are designed to form the core to be taken by the

drill. In addition thereto the hollow cutter 3 is provided with a plurality of radial fins or plates 18 extending down, preferably flush with the edges of the mill teeth 17 which plates or fins 18 constitute outer cutters operative to enlarge the hole formed by the drill and assist in taking the core. Such cutters 18 are preferably made of sufficient size so that the hole, after the core is taken, requires no reaming for further drilling; 19 indicates a plurality of bracing fins on the tubular cutter 3 engaging the lower end of the joint 2 to strengthen the drill.

15 The rotary core drill herein described thus contains but a single barrel, the customary outer barrel being dispensed with and is unnecessary, due to the provision of the outer cutters upon the hollow cutter 3 in place of employing such customary outer barrel for supporting the cutters. The flushing fluid supplied to the drill is passed through the pipes 15 which are welded to the tube 1 so as to constitute an integral part thereof and the entire rotary core drill is of rigid construction well suited for taking all cores in deep oil wells.

It will be noted that the flushing passages 16 discharge at a point above the upper end 20 of the cutters 18 and a substantial distance from the mill teeth 17 of the hollow cutter 3. The distance between the discharge point of such flushing fluids and the mill teeth 17 is in practice preferably over eight inches 25 and permits the flushing fluid to be discharged where the pulsations of the pump forcing the fluid to the bottom of the well will not act at the mill teeth 17 to disintegrate the core being taken by the drill.

40 Actual tests with a core drill of this inven-

tion discloses that the core taken is at all times void of any disintegration due to the action of the flushing fluid supplied to the drill.

While the form of rotary core drill herein particularly described is well suited to accomplish the purpose of this invention, it is understood that various modifications may be made without departing from the spirit of the invention. The invention is of the scope set forth in the appended claims.

We claim:

1. A rotary core drill comprising a core receiving barrel having a plurality of pipes welded to the barrel, core forming cutters 45 at the lower end of the drill, core enlarging cutters secured to the lower end of the drill, and a self closing valve at the upper end of said barrel.

2. A rotary core drill, which comprises 50 a single barrel having core receiving means, means forming exterior flushing passages extending downwardly along the core receiving means, a hollow cutter carrying core forming cutters and bore enlarging cutters, 55 the flushing passages discharging more than eight inches above the core forming cutters of the drill.

3. A rotary core drill comprising a core receiving barrel, a core cutting head connected with the barrel and having core cutting teeth, radial bore enlarging cutters integral therewith, and a plurality of pipes placed against the side of said core receiving barrel for conveying flushing fluid to the 70 vicinity of said core cutting head.

Signed at Los Angeles, California, this 6th day of Sept. 1924.

GEORGE KAMMERER.
FRANK HILL.
